UNITED STATES PATENT OFFICE.

JOHN STEWART GRIFFIN, OF ROSLYN, WASHINGTON.

SHAFT-POLISHING MACHINE.

No. 895,364.

Specification of Letters Patent.

Patented Aug. 4, 1908.

Application filed April 4, 1907. Serial No. 366,308.

To all whom it may concern:

Be it known that I, JOHN STEWART GRIFFIN, a citizen of the United States, and a resident of Roslyn, in the county of Kittitas 5 and State of Washington, have invented a new and Improved Shaft-Polishing Machine, of which the following is a full, clear, and exact description.

This invention relates to machinery for 10 polishing shafting.

The object of the invention is to produce a machine of this class which is simple in construction, and which is provided with automatic means for feeding the shaft to the 15 rolls.

Further objects of the invention will appear hereinafter.

The invention consists in the construction and combination of parts to be more fully 20 described hereinafter and particularly set forth in the claims.

Reference is to be had to the accompanying drawings forming a part of this specification, in which similar characters of reference indicate corresponding parts in all the 25 figures.

Figure 1 is a plan of a machine constructed according to my invention; Fig. 2. is a front elevation of the machine shown in Fig. 1; 30 Fig. 3 is an end elevation showing the end disposed at the left as viewed in Fig. 2; Fig. 4 is a vertical cross section through the machine; Fig. 5 is a horizontal cross section taken through the machine at the point 35 where the shaft or "work" lies, and this view illustrates especially the means for holding the shaft between the polishing rolls; the point at which this cross section is taken is indicated by the line 5—5 in Fig. 6; Fig. 45 6 is an end elevation of the housings or frame of the machine, and illustrating the manner in which the shaft guides are attached in position; Fig. 7 is a vertical cross section upon an enlarged scale, taken upon the line 7—7 45 of Fig. 1, and illustrating the mechanism for drawing the polished shaft from the machine; and Fig. 8 is an elevation showing a portion of the side of the machine opposite to that illustrated in Fig. 2; this view is to 50 further illustrate details of the construction.

Referring more particularly to the parts, and especially to Figs. 1 and 2, 1 represents the frame of the machine, which comprises four housings or columns 2 which are connected in opposite pairs by caps or cap

plates 3, the said cap plates being securely held in position by suitable cap nuts 4. As indicated most clearly in Fig. 4, between the housings, a main roll 5 is mounted rotatably in a central position, and above this roll 60 there is rotatably mounted an adjustable roll 6, the trunnions 7 of the said roll being rotatably mounted in movable boxes or bearings 8 which are guided vertically between the columns. This roll 6 is normally held in an elevated position by means of a transverse bar 9 which extends under the boxes as indicated, the ends of the said bar being provided with bolts 10 which pass upwardly through lugs 11 projecting from the outer sides of the columns. The bolts 10 extend above the lugs 11, and around them helical springs 12 are arranged, which thrust against nuts 13 on the upperends of the bolts. The arrangement is such that the springs 75 tend to pull the bar toward an elevated position, and in this way the roll 6 is normally held elevated.

The adjacent side faces of the columns 2 are provided with substantially U-shaped 80 sockets 14, and these sockets afford means for holding in position a pair of oppositely disposed sleeves 15. The manner of mounting these sleeves in position is clearly shown in Fig. 5; they are of substantially rectangular form, provided at their extremities with fins 16 which are received in the sockets 14 as indicated. Behind the fins, keys 17 are inserted in the sockets, which hold the sleeves in position, as shown in Figs. 5 and 6. 90 Each of these sleeves 15 is provided with a longitudinally disposed slot 18, which extends substantially throughout its entire length. In these slots I provide guide plates 19 respectively, which extend through the sleeves from the rear, so that the forward edges 20 of the guide plates lie adjacent to each other, as shown in Fig. 5. As shown in Fig. 4, these forward edges of the guide plates are slightly concave so as to conform 95 to the shape of the shaft or "work" 21 which is being polished in the machine. In order to hold the guide plates 19 securely in position, the upper sides of the sleeves 15 are provided with set screws 22 which clamp the 100 plates in position. In order to enable the plates to be adjusted toward or from the shaft 21, their rear edges are provided with downwardly extending ears 23. Similar ears 24 are provided on the lower sides of the sock- 105 110

ets, and the ears 23 and 24 are connected by adjusting screws 25 as shown in Fig. 4. By screwing up or unscrewing these adjusting screws, evidently the guide plates may be adjusted in or out as desired.

From the caps 3, bearings 26 are suspended by bolts 27, as shown in Fig. 4, and in these bearings there is rotatably mounted a main shaft 28. These bearings are held securely against rising, if they should be forced upwardly, by means of stout backing screws 29 which pass down through the caps and seat against the upper sides of the bearings.

In order to brace the columns and make the entire frame structure very rigid, the upper portions of the columns are connected by horizontal tie rods 30, as shown in Figs. 3 and 4.

Over the bearings or boxes 8 the shaft 28 is provided with rigid cam collars 31; a portion of the circumference of these cam collars is cut away so as to form a circumferential recess 32 as shown in Fig. 4, and the surface of the collars at the point 33 is slightly depressed with respect to the surface of the collars at the point 34; in other words, the radius of the collars increases slowly from one side of the recess 32 to the other, the amount of increase being, under ordinary circumstances, about an eighth of an inch. From this arrangement it should be understood that when the shaft 28 is rotated, the collars will operate to depress the boxes 8, while the cam surface is in contact with the upper sides of the boxes, and, furthermore, when the recesses 32 are opposite the boxes, they will become slightly elevated through the upward pressure of the springs 12. At the point where the cam collars 31 touch the boxes 8, I provide wear plates 35.

The main shaft 28 is driven by a main gear wheel 36, and this gear wheel is driven by a pinion 37 on an auxiliary shaft 38 mounted in suitable bearings 39 at the side of the machine. As shown especially in Figs. 1 and 3, this shaft 38 extends to the left side of the machine, and is provided with a gear wheel 40 which meshes with a pinion 41 which is rigidly attached to the trunnions 7 of the adjusting roll 6. A similar pinion 42 is provided, which is rigidly attached to the roll 5, from which arrangement it follows that when the shaft 38 is rotating, the rolls 5 and 6 will be rotated in the same direction.

At the left of the machine, as indicated in Fig. 1, there is formed a feed table 43, and at the right of the machine there is constructed a delivery table 44. The feed table 43 consists of a feed base 44^a, in the upper portion of which a plurality of rollers 45 are rotatably mounted, said rollers being in alinement with the shaft 21, and being grooved so as to enable them to advance the shaft into position between the rollers 5 and 6. Between

the rollers 45, the upper face of the feed table is provided with feed rests 46, which are grooved like the rollers 45 so as to conform to the shape of the shaft treated in the machine. The shafts 47 of the rollers are extended at the rear side of the machine, and provided with gear wheels 48 which are driven from pinions 49, the said pinions being mounted on stub shafts 50, the outer ends of which are provided with bevel gears 51. The arrangement at the delivery table is substantially similar to that described for the feed table. At this point a plurality of delivery rollers 52 are provided, mounted between rests 53, and the said delivery rollers 52 are similar in construction to the rollers 45; they are driven, also, in a similar manner, through the medium of rigidly connected gear wheels 54 driven from stub shafts 55, the said stub shafts being provided with bevel gears 56. Adjacent to the bevel gears 51 and 56, there is mounted in the machine a longitudinally disposed feed shaft 57, and on this feed shaft (referring especially to Figs. 3 and 8) there is loosely mounted a belt pulley 58 adapted to be driven continuously when the machine is running, by means of a belt 59. The said belt 59 is driven from a cam 60 rigidly attached on the end of the main shaft 28. In addition to this function of acting as a pulley to drive the belt pulley 58, the cam 60 operates to control the operation of the feed rolls and delivery rolls. For this purpose, on its outer face, the cam 60 is provided with a cam block 61, of curved form, and this cam block operates once in each revolution of the cam, to rock a cam lever 62. The manner of mounting this cam lever is clearly shown in Fig. 3; it is pivotally attached upon the extremity of a post 63 which projects horizontally from one of the columns 2. This post 63 extends through the opposite side of the column, to which it is attached, and is provided with an adjusting nut 64 at this point, which nut is adapted to be screwed down against a plurality of washers 65, of rubber or similar compressible material, the said washers being arranged between the nut and the face of the column, as shown. Against the face of the column opposite to the washers, a shoulder 66 on the post seats. The purpose of this peculiar construction for mounting the post will appear more fully hereinafter. The lower end of the lever 62 is formed into a fork 67 and this fork engages with a sliding cone clutch collar 68 which is feathered or splined on the feed shaft 57. This clutch collar 68 cooperates with a corresponding clutch member 69 which is formed rigid with the belt pulley 58. From this arrangement it should be understood that when the upper end of the lever 62 is forced outwardly by the cam, the clutch faces of the members 68 and 69 will be closed, and when closed, the belt 59 will rotate the shaft 57; 130

hence, it should now be understood that an intermittent feed movement will be given to the feed rollers and delivery rollers.

It should be understood that the grooved faces of the feed rollers and delivery rollers are normally slightly depressed with respect to the rests 46 and 53 of the feed table and the delivery table. I provide automatic means for slightly elevating these rollers 13 when the feed shaft 57 is rotating. For this purpose, I mount the feed rollers and delivery rollers in movable boxes 70, which are vertically guided in grooves 71 in the side faces of the tables. Against the lower faces 15 of these boxes 70, as indicated most clearly in Fig. 2, a plurality of lifting toes 72 are arranged, the said lifting toes being rigidly attached to transverse rock shafts 73. These rock shafts 73 at the rear side of the machine, 29 have rigidly attached to them rocker arms 74, which extend upwardly as indicated in Fig. 8, and these arms 74 are all connected together by a rocker bar 75 which extends continuously from end to end of the machine. 25 The rock shaft 73^a, as indicated in Fig. 8, is provided with an upwardly extending rocker arm 76, and this arm is connected by a link 77 with the lower portion of the cam lever 62. From this arrangement it should be understood 30 that when the lower end of the lever 62 moves toward the left as viewed in Fig. 8, to close the clutch, the rock shaft 73^a will be rotated toward the left, and through the medium of the rocker bar 75, all of the toes 35 72 will be moved in a direction to raise the bearing blocks 70. In this way all of the feed rollers and delivery rollers are raised so as to bring their faces above the surface of the tables in which they are mounted; hence, 40 the rotation of the rollers will advance the shaft longitudinally between the rolls 5 and 6.

It should be understood that the cam block 61 is so placed upon the cam 60 that this feed movement of the feed shaft occurs 45 when the adjustable roll 6 is in its elevated position.

The special arrangement for mounting the post 63 will now be referred to again: The construction described has been adopted in 50 order to give a certain flexibility to the action of the lever in closing the clutch members 68 and 69. In this connection it should be understood that the tension or outward pull which the post 63 will receive, by reason of 55 the pressure between the members of the clutch, will operate to compress the washers 65, so that these washers collectively act as a cushion or spring.

Referring now specially to Figs. 1 and 7, 60 I will describe the mechanism for discharging the polished shaft from the machine: For this purpose, the rests 53 of the delivery table are provided with slots 78, which extend transversely of the table. At the forward side of the table, ejectors 79 are pivot-

ally mounted, and these normally lie just below the slots, as indicated in Fig. 7. At their inner extremities they are formed with upwardly projecting teeth 80 respectively, and are adapted to be pushed upwardly by means of links 81, the said links being pivotally attached below to rocker arms 82, which are rigidly attached to a rock shaft 83. This rock shaft 83 is adapted to be rocked by the attendant, by means of a lever 84 which extends upwardly near the end of the machine as shown. When the lever is rocked toward the left so as to assume substantially the position shown in dotted lines, the ejectors 79 move up through the slots so as to lift the polished shaft off of the table and allow it to roll down at the front of the machine.

The mode of operation of the machine will now be briefly described: The shaft to be polished is placed upon the feed table 43 in any suitable manner, and as the main shaft 28 revolves, the adjustable roll 6 will move upwardly, when the recesses 32 of the cam collars are over the boxes 8. At this time the springs 12 will pull the adjustable roll 6 upwardly so that a space is presented between the rolls 5 and 6 into which the shaft to be polished may be advanced. At this time the cam block 61 operates the lever 62 so as to close the clutch post of the members 68 and 69. In this way the feed shaft 57 will be rotated and the feed rollers will be driven. At the same time, the rock shaft 73 will be rocked so as to raise the rollers on the toes 72. The feed rollers will then operate to advance the shaft longitudinally into the space between the rolls 5 and 6. As the rotation of the shaft 28 proceeds, the movable roll 6 will be depressed upon the shaft so as to reduce its diameter and polish it. For the usual class of work, the amount of reduction of diameter will be about an eighth of an inch, but in finer work, the reduction may be not more than a sixteenth of an inch. By the periodical advancing movement of the shaft between the rolls, the rolling or polishing operation progresses until the shaft has passed completely through the rolls to the delivery table, where it is ejected in the manner described above.

The thickness of the guide plates 19 will depend upon the diameter of the shaft which is being rolled. It should be understood that the upward movement of the feed and delivery rollers is so slight that it has substantially no effect upon the relation of the gear wheels through which the rollers are driven, and, likewise, the vertical movement of the movable roll 6 is not sufficient to materially change the relation of the gear wheels 12 40 and 41, as will appear from an inspection of Fig. 3. But if the diameter of the shaft to be polished is from 2 to 4 inches more or less it will be necessary to provide for a horizontal adjustment of the shaft 38.

Having thus described my invention, I claim as new and desire to secure by Letters Patent:

1. In a shaft polishing machine, in combination, a frame, a pair of reducing rolls mounted therein, means for advancing or withdrawing said reducing rolls with respect to each other, a feed table, a plurality of feed rollers mounted in said table and adapted to advance the shaft into the space between said rolls, said feed rollers being normally depressed out of contact with the shaft as it lies on said table, a member controlled by said reducing rolls and affording means for raising said feed rollers above the surface of said table when said rolls are withdrawn with respect to each other, and means controlled by said member for rotating said feed rollers to advance the shaft when said rolls are withdrawn with respect to each other. 10
2. In a shaft polishing machine, in combination, a frame, a pair of rolls mounted therein, means for advancing or withdrawing said rolls with respect to each other, a feed table having rests adapted to support the shaft to be advanced between said rolls, feed rollers movably mounted in said feed table and normally depressed below the level of said table, and means connecting said rolls and rollers adapted to elevate the latter when said rolls are in their withdrawn position. 20
3. In a shaft polishing machine, in combination, a frame, a pair of rolls mounted therein, a feed table, a plurality of boxes movably guided therein, feed rollers mounted respectively in said boxes, means for advancing or withdrawing said rolls with respect to each other, whereby they may occupy an adjacent or a separated position, and means operating between said rolls and said boxes adapted to elevate said boxes carrying said rollers when said rolls are in their separated position. 30
4. In a shaft polishing machine, in combination, a frame, a pair of rolls mounted therein, means for advancing said rolls toward each other or withdrawing the same from each other, a feed table, a plurality of rollers mounted in said table and adapted to advance the shaft into the space between said rolls, a cam adapted to rotate with one of said rolls, a feed shaft, means for driving said rollers from said feed shaft, a clutch on said feed shaft, and means for closing said clutch by said cam. 40
5. In a shaft polishing machine, in combination, a frame, a pair of rolls mounted therein, means for advancing said rolls toward each other or withdrawing the same from each other, a feed table, a plurality of rollers mounted in said table and adapted to advance the shaft into the space between said rolls, a cam adapted to rotate with one of said rolls, a feed shaft, means for driving said said rolls, a feed shaft, means for driving said said feed shaft, and means for closing said clutch by said cam. 50
6. In a shaft polishing machine, in combination, a frame, a pair of rolls mounted therein, means for advancing said rolls toward each other or withdrawing the same from each other, a feed table, a plurality of rollers mounted in said table and adapted to advance the shaft into the space between said rolls, a cam adapted to rotate with one of said rolls, a feed shaft, means for driving said said feed shaft, a clutch on said feed shaft, means for closing said clutch by said cam, said rollers being normally disposed below the level of said table, and means for raising said rollers actuated by said rolls when said rolls are separated. 60
7. In a shaft polishing machine, in combination, a frame, a pair of rolls mounted therein, means for advancing said rolls toward each other and separating the same, a cam rotating with one of said rolls, a feed table, a plurality of rollers mounted in said feed table, a feed shaft, means for driving said rollers from said feed shaft, a clutch on said feed shaft, means for closing said clutch by said cam, said rollers being normally depressed below the level of said feed table, and mechanism actuated by said cam for raising said rollers when said rolls are separated. 70
8. In a shaft polishing machine, in combination, a frame, a pair of rolls mounted therein, means for advancing said rolls toward each other and separating the same, a feed table, a plurality of boxes mounted to slide vertically therein, feed rollers carried respectively in said boxes, a feed shaft, means for driving said rollers from said feed shaft, a clutch on said shaft, a cam rotating with one of said rolls, a cam lever actuated by said cam and affording means for closing said clutch, and mechanism actuated by said lever for raising said rollers. 80
9. In a shaft polishing machine, in combination, a frame, a fixed roll rotatably mounted therein, a movable roll mounted in said frame adjacent to said fixed roll, boxes supporting said movable roll, a main shaft, collars carried on said shaft and having cam faces adapted to depress said boxes to force said movable roll toward said fixed roll, said collars having recesses in the faces thereof, means tending to raise said boxes whereby said movable roll will be elevated when said recesses are passing said boxes, feed rollers adapted to advance a shaft between said rolls, and means controlled by said rolls for actuating said feed rollers when said recesses are adjacent to said boxes. 90
10. In a rolling machine, the combination of a frame, a pair of rolls adapted to operate 100

upon a shaft when it is placed between them in a position longitudinal to the axis, said rolls so constructed and arranged that the working portions of the faces will advance 5 and recede at certain timed intervals, means adapted to support the shaft and feed it longitudinally into the space between said rolls, and means coöperating with the reducing rolls and the feeding means constructed and 10 arranged to operate the feeding means so as to feed the material at the time when the adjacent working portions of the rolls are in the receded position.

11. In a shaft rolling machine, in combination, a frame, a pair of reducing rolls adapted 15 to operate upon a shaft when placed therebetween in a position longitudinal to the axes

of said rolls, said rolls being so constructed and arranged that they will advance toward each other and recede at certain timed intervals, means for feeding the shaft longitudinally into the space between said rolls, and means coöperating with said rolls and said feeding means constructed and arranged to operate the feeding means so as to feed the 20 shaft at the time that the said rolls are in their receded position. 25

In testimony whereof I have signed my name to this specification in the presence of two subscribing witnesses.

JOHN STEWART GRIFFIN.
